D. H. MOSTELLER,
RECEPTACLE COVER,
APPLICATION FILED JUNE 15, 1918.

1,310.836

Patented July 22, 1919.

Inventor:
Doris H. Mosteller,
By *Frank King*,
Attorney.

UNITED STATES PATENT OFFICE.

DOSIER H. MOSTELLER, OF OAK PARK, ILLINOIS.

RECEPTACLE-COVER.

1,310,836.

Specification of Letters Patent. Patented July 22, 1919.

Application filed June 15, 1918. Serial No. 240,109.

To all whom it may concern:

Be it known that I, Dosier H. Mosteller, a citizen of the United States, residing at Oak Park, Cook county, Illinois, have invented certain new and useful Improvements in Receptacle-Covers, of which the following, taken in connection with the drawings, is a description.

My invention has for its object the production of a receptacle cover through which access may be had to the contents of the receptacle without removing the cover.

A further object of my invention is to provide a cover of the class described, which can be mounted on receptacles of various sizes and releasably locked thereto.

In many localities vendors of certain foods and confections are required by law to keep them in covered receptacles, and the receptacles now in use require the use of both hands in uncovering and removing articles therefrom. It is a further object of my invention to provide a receptacle for such articles, and particularly for such articles as ice cream cones, from which the articles can be removed with one hand while opening and closing the cover to the receptacle.

My invention consists in the construction and novel arrangement of parts hereinafter described and illustrated, and I wish to be understood as contemplating such modifications and variations as come within the scope of the appended claims, and in these drawings:

Figure 1 is a side elevation of a receptacle equipped with my invention: Fig. 2 is a cross section of the same, taken on line 2-2 of Fig. 1: Fig. 3 is a bottom plan view of the cover shown in Figs. 1 and 2: and Figs. 4 and 5 are respectively a side elevation and plan view of a modified form of attaching device.

Referring to these drawings, 5 is a receptacle having a circumferential shoulder 6 near the upper extremity thereof, as shown in Figs. 1 and 2, terminating in a neck 6^a, the receptacle being of any size suitable for the purpose for which it is to be used. The cover, 7, is a disk having a downwardly extending flange, 8, on the periphery thereof, the purpose of said flange being to exclude any particles of foreign matter. The cover, 7, has an opening, 9, therein, of sufficient size to permit the passage of the hand of a person, and the articles desired to be kept

in the receptacle. Access to the contents of the receptacle may be had through said opening without removing the cover.

Positioned over the opening, 9, is a door, 10, hingedly or otherwise secured to said cover at 11. The outer end of the door 10, is turned in an upward direction, as shown at 12, to facilitate the raising thereof.

On the under side of the cover, 7, are rigidly mounted supporting members, 13, preferably of U shape, as shown in Fig. 2. The locking members, 14, are slidably mounted through openings in the supporting members, 13. When extended, the outer ends, 15, of the locking members, 14, are adapted to engage the lower side of the circumferential shoulder, 6, thereby locking the cover to the receptacle. When extended in outward direction, the locking members, 14, are held in such position by the frictional engagement between the ends, 14^a, of the locking members, which are bent as shown in Fig. 3, and the edges of the supporting members, 13.

The locking members, 14, are preferably arranged at an oblique angle as shown in Fig. 2, so that the outer ends thereof will be in better conformity with the under side of the shoulder, 6.

When the cover is to be put in place, it is placed upon the upper edge of the receptacle, the top of the receptacle being inside of the flange, 8, and the supporting members, 13, being inside of the receptacle. The door, 10, is then raised, so that the locking members may be adjusted. The locking members, 14, are then extended until further outward movement thereof is precluded by the engagement of the outer ends, 15, with the receptacle, under the shoulder, 6, and the frictional engagement with the edges of the supporting members, 13.

When it is desired to remove the contents of the receptacle, the door, 10, is raised by the hand contacting with the lip, 12, which is raised to remove the contents of the receptacle, the door closing by gravity upon the withdrawal of the person's hand from the receptacle.

It will be observed by the construction of the members, 14, that my receptacle cover may be used upon receptacles varying in size two or more inches in diameter, thereby permitting the device to accommodate a large variety of receptacles, such as are now on the market.

In Figs. 4 and 5 I have shown a slightly modified form of construction wherein I employ a rubber faced roller 16 mounted upon the end of the engaging roller 14. This roller is provided with a longitudinal opening preferably between the axis and periphery of the roller as shown more particularly in Fig. 4. The device as thus constructed is adapted for use with receptacles having straight sides, the tendency of the roller to turn forcing it closer to the wall contacted therewith and at all times holding the cover in proper position.

I claim:

- 15 1. The combination with a receptacle having a circumferential shoulder, of a cover comprising a disk having a downwardly extending flange on its periphery, said cover having an opening of relatively small size 20 therethrough, a door positioned over said opening, and hingedly mounted on said cover, a plurality of independent supporting members mounted on the under side of said cover; and a plurality of independent 25 locking members adapted to positively engage said circumferential shoulder.
2. The combination with a receptacle having a circumferential shoulder, of a cover comprising a disk having an opening of relatively small size therethrough; a door positioned over said opening and adapted to be closed by gravity; a plurality of U shaped supporting members rigidly mounted on the under side of this cover; a plurality of independently operating locking members 35 mounted on said supporting members, said locking members being adapted to positively engage said circumferential shoulder and

hold the cover in locked position with relation to the receptacle.

3. The combination with a receptacle having a circumferential shoulder, of a cover comprising a disk having a relatively small opening therethrough; a door positioned over said opening and movably mounted on 45 said cover; a plurality of U shaped supporting members, rigidly mounted on the under side of said cover; a plurality of independently operating locking members slidably mounted in said supporting members, said 50 locking members being adapted to positively engage said circumferential shoulder at their outer ends when extended, and means for holding said locking members in extended position.

4. The combination with a receptacle having a circumferential shoulder, of a cover comprising a disk having a relatively small opening therethrough; a door positioned over said opening and movably mounted on 60 said cover; a plurality of supporting members mounted on the under side of said cover; a plurality of independently operating locking members slidably mounted in said supporting members at each side of 65 said door opening, said locking members being positioned at an oblique angle to a vertical line, and being adapted to be adjusted in positive engagement with said shoulder; and means on said locking members for holding said members in extended position by frictional engagement with the edges of said supporting members.

In testimony whereof I have signed this specification.

DOSIER H. MOSTELLER.
